UNITED STATES PATENT OFFICE.

HERBERT M. FIRTH, OF NILES CENTER, ILLINOIS.

DESIGN FOR A LIGHT FIXTURE.

Application filed March 8, 1928. Serial No. 25,762. Term of patent 7 years.

To all whom it may concern:

Be it known that I, HERBERT M. FIRTH, a citizen of the United States, residing at Niles Center, in the county of Cook and State of Illinois, have invented a new, original, and ornamental Design for a Light Fixture, of which the following is a specification, reference being had to the accompanying drawing, forming part thereof.

The figure is a side elevation of a light fixture showing my improved design.

I claim:

The ornamental design for a light fixture as shown.

HERBERT M. FIRTH.
